Primary Examiner — Christy Nemeth

CLAIM

The ornamental design for an electrical receptacle, as shown and described.

DESCRIPTION

FIG. 1 is a front, left perspective view of an electrical receptacle, showing our new design;

FIG. 2 is front view thereof;

FIG. 3 is rear view thereof;

FIG. 4 is a left side view thereof;

FIG. 5 is right side view thereof;

FIG. 6 is a top view thereof; and,

FIG. 7 is a bottom view thereof.

The broken lines in the drawings are for the purpose of illustrating portions of the article that form no part of the claimed design.
